UNITED STATES PATENT OFFICE

2,302,425

TELEVISION APPARATUS

Franklin M. Deerhake, Schenectady, N. Y., assignor to General Electric Company, a corporation of New York

Application October 26, 1940, Serial No. 363,021

6 Claims. (CL 178—7.3)

My invention relates to television apparatus, and in particular to apparatus for reinserting, at the output of a video amplifier, low frequency and direct current components of video signals which are attenuated or lost in transmission through the amplifier.

In present-day television systems an image to be transmitted is usually scanned in a series of lines, and electrical signals are developed which are representative of the brightness of each elemental picture component of the image. These signals must, in general, convey two kinds of information: first, the relative brightness of the picture elements, determined by the details of the image, and second, the average absolute brightness of the picture elements, determined by the background illumination. Thus, the signals must represent both instantaneous and steady state conditions and contain a wide range of frequency components down to and including direct current components. All these components must be present in the final signals which are utilized in the receiving apparatus to reproduce the image, if distortion is to be avoided.

Amplifiers capable of amplifying low frequencies and direct currents, as well as higher frequencies extending over the wide range of frequencies present in television video signals, are very costly and difficult to build. Hence, it is common practice to use more economical resistance-capacitance coupled amplifiers in both television transmitting and receiving apparatus. Since low frequency and direct current components are attenuated or lost in transmission through such amplifiers, it is necessary to reinsert these components in the output to restore all components of the video signals to their proper relative values. Accordingly, it is a main object of my invention to provide improved circuits for reinserting these components in the output of a video amplifier.

A preferred form of video signal is one in which increases in signal amplitude are representative of decreases in illumination, and vice versa. Between successive trains of picture signals blanking pedestals are inserted which have an amplitude substantially corresponding to black in the picture image. These pedestals serve to blank out the retrace portions of the scanning pattern in a manner familiar to the art. They also serve to establish a fixed reference level for the synchronizing pulses, which comprises impulses of greater amplitude superimposed on the pedestals and extending into the region com-

monly designated as the infra-black or blacker-than-black region.

Since the fixed level of the pedestal portions of the video signal corresponds to black in the picture image, it provides a very convenient reference level to which may be referred the instantaneous picture signal intensity, corresponding to the absolute brightness of the picture elements of image. The average background illumination is proportional to the distance from this level to the average value of the picture signal. As will be pointed out in greater detail in the following specification, if a video amplifier is capable of transmitting, without substantial distortion, the wave form of the pedestal portions and all but the lowest frequency components of the picture signal portions, a peak rectifier circuit coupled to the amplifier output may be utilized to develop signals substantially proportional to the non-transmitted low frequency and direct current components. These may then be mixed with the amplifier output and supplied to a utilization circuit, usually a final video amplifier or a modulator. The types of amplifier and modulator tubes which are now available for television service require a low impedance input circuit for stable operation. However, the rectifier output must inherently be of high impedance and the problem is presented of coupling it directly to the utilization circuit without causing circuit instability. Furthermore, the reinserted components must bear the proper amplitude relationships to the transmitted signal components.

It is therefore a further object of my invention to provide improved means for reinserting low frequency and direct current components in the video amplifier output in the proper proportions and for directly coupling the reinsertion circuits to a utilization circuit so as to insure stable operating characteristics.

The features of my invention which I believe to be novel are set forth with particularity in the appended claims. My invention itself, however, together with further objects and advantages thereof, may best be understood by reference to the following description taken in connection with the accompanying drawing, in which Fig. 1 diagrammatically represents portions of a television apparatus embodying my invention, and Figs. 2a through 2d are representative of the wave forms of video signals which will be referred to for a better understanding of the operation of my invention.

Referring now to Fig. 1, video signals to be

amplified are supplied from any suitable source, not shown, to the input of a video amplifier, illustrated as a pentode 10. As shown, the signals are coupled to the control grid of the amplifier 10 by means of a resistance-capacitance coupling network 11, 12. A normal operating bias is impressed on the control grid by means of any suitable potential source, not shown, connected between the lower end of resistor 11 and the grounded cathode of amplifier 10. The output circuit for the amplifier 10 extends from the anode through a load circuit serially comprising load resistors 13 and 14, an inductance element 15, a decoupling resistor 16, a suitable source of anode potential, indicated by the terminals 17 and 18, to the grounded cathode of the amplifier. The decoupling resistor 16 and potential source 17, 18 are by-passed for signal frequencies by the capacitor 30. The element 15 is a shunt-peaking inductance commonly employed in amplifiers of this type for improving the high frequency response characteristics.

While the video amplifier 10 of Fig. 1 has been illustrated as a single stage, it will be observed that it may comprise a plurality of stages each of which may be similar to the one just described.

Coupled across the output of the amplifier 10 is a rectifier 19, illustrated as a duo-diode having its cathode electrodes and anode electrodes respectively connected together to function as a single diode rectifier. The cathodes of the rectifier 19 are connected to the anode of the video amplifier 10 through a capacitor 20 and the anodes are connected to the cathode of the amplifier 10 through a bypass capacitor 31. The anodes are also connected to a movable tap 23 on a bias potentiometer 21. The potentiometer 21 is connected across a suitable source of potential, indicated by the terminals 22 and 18, which is poled to maintain the right-hand end of the potentiometer negative. The unidirectional potential of the anodes of the rectifier 19 with respect to ground may be adjusted by adjusting the movable tap 23.

Connected in shunt to the diode 19 is a diode load resistor 24. These elements, together with the capacitor 20, form a diode detection circuit of the shunt type for rectifying the signals appearing in the output of the amplifier 10. The rectified signals appear across the load resistor 24. This circuit develops low frequency and unidirectional signals, proportional to those present in the video signals supplied to the input of amplifier 10, in a manner shortly to be described in greater detail.

The resistor 24 is also included in the grid circuit of a triode amplifier 25. This amplifier is connected in a cathode-coupled circuit, sometimes called a "cathode-follower" circuit. The anode of the amplifier 25 is connected directly to the positive terminal 17 of the source of anode potential and the cathode thereof is connected to the grounded terminal 18 of this source through resistors 26 and 27 and the potentiometer 21. The grid is connected directly to the upper terminal of the load resistor 24.

It will be observed that the resistors 26 and 27 are included in both the grid and anode circuits of the amplifier 25, thus providing a large amount of cathode degeneration. When operated in this fashion the amplifier has a gain somewhat less than unity, which is practically constant for relatively low frequencies down to and including unidirectional components. The gain is always less

than unity but it can be made very nearly equal to unity by using a high gain amplifier. Furthermore, this circuit permits stable operation with a relatively high value of resistance in its grid circuit and low resistance in its common cathode circuit.

The resistor 27 is connected across the terminals of a suitable utilization circuit. As illustrated, it is connected between the grid and cathode of a tetrode 28 through the bias potentiometer 21. The tetrode 28 and associated circuits may constitute a final power amplifier for the video signal; or, in a television transmitter, it may comprise a modulator stage. A portion of the video signal output of the amplifier 10, appearing across the load circuit elements 14, 15 and 16, is also coupled to the grid of the amplifier 28 through the capacitor 29.

The operation of the circuit of Fig. 1 will best be understood in connection with the wave forms of television signals illustrated in Fig. 2. Fig. 2a is representative of a well-known form of video signal over the interval including two blanking pedestals, i. e., including the scanning of one line. The picture signal portions, corresponding to the details of the picture image being transmitted, are indicated by the reference numeral 39. Instantaneous variations in the complete video signal, including the picture signal portions 39 and also the pedestal and synchronizing portions 41 and 43, take place about some alternating current axis, such as is indicated by the dashed line 40. As previously mentioned, the pedestal portions 41 of the signal assume a fixed reference level corresponding to black in the picture image. This level is indicated by the dashed line 42. The synchronizing pulses 43 extend a definite distance above this level into the infra-black region. The direct current component of the video signal during the interval represented is proportional to the distance between the axes 40 and 42.

A video signal produced by scanning the same image line, but with decreased background illumination, is graphically represented in Fig. 2b. It will be observed that the wave form of the picture signal 39 is the same as in Fig. 2a, but the direct current component of the signal is less than before, corresponding to a darker image. The pedestals 41 and synchronizing pulses 43 lie on the same threshold level 42 as before.

Thus, for proper rendition of the absolute brightness values of all elements of a scanned image, the pedestal portions must establish a fixed reference level. In order to convey the background brightness and variations therein, the video signal must contain corresponding low frequency and unidirectional components with respect to this level.

If such video signals are supplied to the input of the amplifier 10 of Fig. 1, the background components will necessarily be attenuated or lost in transmission through the capacitor 12. For example, the signals of Fig. 2a and Fig. 2b will appear on the grid of amplifier 10 generally as represented in Figs. 2c and 2d, respectively. If the capacitor 12 is large enough, the wave forms of the pedestals 41, the synchronizing pulses 43 and the picture signal 39 will be preserved, but the signal will be referred to the arbitrary alternating current axis 40 such that the areas of the video signal above and below this axis are substantially equal. It will be seen that this axis has no relation to the background illumination

and that the pedestals no longer lie along a fixed reference level.

The diode detector 19, together with the capacitor 20, resistor 24, effects peak rectification of the amplified video signal supplied from the output of the amplifier 10. The detector is so poled that the pedestal and synchronizing pulses tend to drive its anode positive. The time constant of the capacitor 20 and resistor 24 is made long relative to the interval between adjacent pedestals. Therefore, through the well-known detector action a fixed reference level 44 for the rectified signal is established just slightly below the tips of the synchronizing pulses. The rectified potentials appearing on resistor 24 correspond to the distance from this level to the average level 40 of the video signals. The slight difference between this new reference level and the level of the blanking pedestals is nearly constant since the height of the synchronizing pulses is constant, and this is easily eliminated by a simple adjustment of other portions of the reinsertion circuits now to be described.

It should be noted that, while the time constant of capacitor 20 and resistor 24 should be long enough to permit rectification of the peaks of the synchronizing pulses, it should not be too long. Otherwise, variations in the intensity of the background illumination will not be faithfully reproduced. As a rough criterion the time constant should be short relative to the time interval required to scan one complete picture image.

The potentiometer 21 performs several important functions. In the first place, by reason of the potential drop across the portion of this potentiometer to the right of the tap 23, a small current flow is maintained through the diode 19 and resistor 24. This provides an initial bias on the diode 19 which insures linearity of operation even in the presence of very weak signals. In the second place, the potential drop across the resistor 24 biases the grid of the amplifier 25, which in turn determines the minimum current flowing through resistors 26 and 27. It will be observed that a negative bias is impressed on the grid of amplifier 28 equal to the total drop across the potentiometer 21 minus the potential drop across resistor 24 due to this current flow. Therefore, adjustment of the tap 23 on the potentiometer 21 simultaneously adjusts the bias potentials applied to the tubes 25 and 28.

Since the rectified potentials developed on the resistor 24 are substantially proportional to the components to be reinserted at the grid of amplifier 28, it might be assumed that amplifier 28 could be directly coupled to this resistor. However, in the usual case the resistor 24 will have a high resistance of several megohms. The inclusion of a high resistance of this order in the grid circuit of amplifier 28 would not be satisfactory. In tubes of the types available for television work, such a connection would result in instability and tube runaway. The cathode-coupled amplifier 25 offers an effective solution to this problem. As previously mentioned, such a circuit permits stable operation with a high value of resistance in its grid circuit and a relatively low value of resistance in its output circuit. It also permits the use of a small triode of a type that is less susceptible to instability than the type of tube required for amplifier 28, which will generally be a power tube.

The resistor 26 is employed to decouple the unavoidable shunt capacity of the cathode of the

amplifier 25 from the grid of the amplifier 28 in order to obtain better high frequency response. That is, this resistance isolates the capacity between the cathode of amplifier 25 and ground from the grid of amplifier 28 and thus reduces attenuation of high frequency currents transmitted through capacity 28 by this cathode to ground capacity. This resistance 26 may be relatively small compared to resistor 27 so that most of the amplifier output appears on the latter resistor.

For a number of causes, the reinserted low frequency and direct current components developed on resistor 27 have amplitudes somewhat less than they would have had if transmitted directly through the video amplifier 10 with the same efficiency as the higher frequency components of the video signal. As previously mentioned, the detector 19 actually establishes a reference level for the rectified signal which differs very slightly from the pedestal level. The cathode-coupled amplifier 25 introduces a small amount of deamplification and a further loss occurs due to the drop through the decoupling resistor 26. The net result is that a loss in voltage of approximately ten per cent may be expected in the reinsertion circuits, in the ordinary case.

The proper proportions of transmitted to reinserted components of the video signal are easily reestablished by connecting the coupling capacitor 29 to a point of lower potential on the output circuit of amplifier 10 than the point to which the capacitor 20 is connected. Thus, the signal impressed on the rectifier 19 is greater than the signal applied to the grid of the amplifier 28 through capacitor 29 by the drop across resistor 13 of Fig. 1. If this drop is made exactly equal to the loss in the reinsertion circuits, perfect restoration of all video signal components at the input to amplifier 28 is achieved. Obviously, it can also be made greater or smaller should over-compensation or under-compensation be desired.

The constants of the component circuit elements of Fig. 1 are subject to considerable variation depending upon the particular case involved. Therefore, although the following values are given for a typical apparatus embodying my invention, it is to be understood that they are only illustrative. These values have been found suitable in a 441-line, double-interlaced transmission system having 60 picture fields per second. The tubes 10, 19, 25 and 28 were types 1852, 6H6, 6SF5 and 6L6, respectively. Other constants follow:

Resistor 13	ohms	100
Resistor 14	do	1,000
Resistor 16	do	10
Capacitor 20	microfarad	.01
Resistor 21	ohms	100,000
Resistor 24	megohms	10
Resistor 26	ohms	8,000
Resistor 27	do	100,000
Capacitor 29	microfarad	.01
Capacitor 30	do	1
Capacitor 31	do	1
Source 17, 18	volts (positive)	300
Source 22, 18	volts (negative)	105

It will thus be seen that my invention provides means for obtaining practically perfect restoration of the low frequency and direct current components with a minimum of distortion, even on weak signals, and insures stable operation.

While I have shown a particular embodiment of my invention, it will of course be understood that I do not wish to be limited thereto since various modifications may be made, and I con-

template by the appended claims to cover any such modifications as fall within the true spirit and scope of my invention.

What I claim as new and desire to secure by Letters Patent of the United States, is:

1. In combination, a source of signal electromotive force having frequencies extending over a band including low frequency and unidirectional components varying with respect to a predetermined signal level, said electromotive force having recurrent portions of an amplitude substantially equal to said level, alternating current translating means for said composite signals, a utilization device having low impedance, and means to reproduce from the output of said translating means currents in said utilization device having said high frequency, low frequency, and unidirectional components in desired relationship with respect to said predetermined level, said means comprising separate paths between said translating means and said utilization device for high frequency and low frequency components, said path for low frequency components including a peak rectifier having a high impedance load, and a cathode follower amplifier connected between said high impedance load and said low impedance utilization device, the cathode of said cathode follower amplifier oscillating above ground and having impedance to ground high at the highest frequencies transmitted through said low frequency path and having low impedance for currents transmitted through said high frequency path, and an impedance between said cathode and said utilization device to reduce attenuation of currents transmitted through said high frequency path by said low cathode to ground impedance.

2. In combination, a source of electromotive force varying in accordance with a televised picture and its background brilliance and having only alternating current components varying with said background brilliance, a utilization device, means to supply to said utilization device high frequency current varying in accord with said televised picture and low frequency and unidirectional currents varying in accord with said background brilliance, said means comprising separate paths between said source and said utilization device for said high frequency currents and for said low frequency and unidirectional currents, said low frequency path having a peak rectifier for said alternating electromotive force, a load resistor therefor, and a cathode follower amplifier connected between said load resistance and said utilization device to transmit to said utilization device said low frequency and background variations, the cathode of said amplifier varying from ground potential at the rate of low frequency background variations in said televised picture and having undesired low impedance to ground for variations of higher frequency, said high frequency path being proportioned to supply said higher frequency variations to said utilization device independently of said cathode follower and in desired relationship to said low frequency and direct current components.

3. In combination, a source of electromotive force varying in accord with a televised image and its background brilliance and having only alternating current components, a peak rectifier for said alternating electromotive force having a load resistance on which appears unidirectional electromotive force varying as the low frequency and background components of said televised picture, an amplifier having input impedance suit-

able for amplification of said alternating electromotive force but too low for direct connection to said load resistance, a cathode follower amplifier connected between said load and said input impedance to supply low frequency and unidirectional components from said load to said amplifier for amplification, and a separate high frequency path between said source and said input impedance to supply high frequency components of the televised picture to said amplifier for amplification thereby.

4. In combination with a source of composite signals extending over a band of frequencies which include low frequency and unidirectional components with respect to a predetermined signal level, said signals having recurrent portions of an amplitude substantially equal to said level, means for translating said composite signals without said components, a diode rectifier coupled to the output of said translating means, means biasing said diode for operation on a substantially linear portion of its operating characteristic, means interconnected with said diode for effecting peak rectification of the translated signals impressed on said diode, thereby to develop low frequency and unidirectional signals substantially proportional to said non-transmitted components, a thermionic amplifier having a load impedance common to its input and output circuits, means coupling said low frequency and unidirectional signals to the input circuit of said amplifier, a utilization circuit adapted to translate substantially all components of said composite signals, means coupling said impedance to said utilization circuit, and means coupling the output of said translating means to said utilization circuit.

5. In television apparatus for translating video signals having components extending over a wide band of frequencies and including very low frequency and unidirectional components with respect to a predetermined threshold level, said signals having portions which extend to said level at intervals, the combination comprising means for amplifying said signals without said low frequency and unidirectional components, means for rectifying said amplified components comprising a diode detection circuit having a time constant which is long relative to the longest interval between said portions, a thermionic amplifier having an output impedance common to its grid and anode circuits, means conductively coupling said detection circuit to said grid circuit, a video signal amplifier having its input circuit conductively coupled to said impedance, whereby low frequency and unidirectional potentials substantially proportional to said non-amplified components are developed on said impedance and impressed upon said input circuit, means for impressing a corresponding proportion of said amplified components upon said input circuit, means for impressing a relatively low positive potential on said diode sufficient to maintain it biased for operation on a substantially linear portion of its characteristic, said low potential also being effective to determine the grid bias potentials on both said amplifiers, and means for varying said low potential to adjust all said bias potentials simultaneously.

6. In television apparatus for translating video signals having components extending over a wide band of frequencies and including very low frequency and unidirectional components with respect to a predetermined threshold level, said signals having portions which extend to said

level at intervals, the combination comprising means for amplifying said signals without said low frequency and unidirectional components, means for rectifying said amplified components comprising a demodulation circuit including an output impedance, said circuit having a long time constant as compared to the longest interval between said portions, an electron discharge amplifier having its grid connected to its cathode through a grid circuit serially including said im- 10

pedance, a decoupling resistance and an output load resistance in the order named, an anode circuit for said amplifier serially including said resistances, means for impressing a fraction of 5 said amplified components across said load resistance, and means conductively coupled to said load resistance and capable of translating substantially all components of said video signals.

FRANKLIN M. DEERHAKE.
